UNITED STATES PATENT OFFICE.

ADRIAN F. BOUTON AND KENT K. STEARNS, OF ELIZABETH, NEW JERSEY.

POCKET TOOTH-BRUSH.

SPECIFICATION forming part of Letters Patent No. 380,080, dated March 27, 1888.

Application filed March 30, 1887. Serial No. 233,089. (No model.)

To all whom it may concern:

Be it known that we, ADRIAN F. BOUTON and KENT K. STEARNS, citizens of the United States, and residents of Elizabeth, in the county of Union and State of New Jersey, have invented certain new and useful Improvements in Pocket Tooth-Brushes, of which the following is a specification.

Our invention relates to the mechanical construction of a tooth-brush adapted to be carried in the pocket or for packing in a valise.

Referring to the drawings, Figure 1 is a full side view of the device. Fig. 2 is a longitudinal sectional view of Fig. 1, the tooth-brush being in a position for use in both of the above figures. Fig. 3 is a top view of the device ready to be placed in the pocket. Fig. 4 is an end view of Fig. 3, the end considered being the right-hand end. Fig. 5 is a sectional view of Fig. 2 at the line X. Fig. 6 is a sectional view at the line Y. Fig. 7 shows the same as Fig. 3, except that the open or right-hand end is provided with a cap or cover; and Fig. 8 is a view of the part which immediately supports the brush, shown in cross-section, and provided with a rubber disk which prevents the entrance of water into the tubular portion of the device.

The tooth-brush in general consists of the combination of an inclosing-tube, *a*, closed at one end by the disk *b*, which carries a helical spring, *c*, a brush-support, *d*, carrying a brush, *e*, and a clamping-spring, *f*, a projection or button, *g*, fastened to the free end of the spring *f*, two holes, *h* and *h'*, the former being located near the closed end of the tube and the latter near the middle, a projection, *i*, within the tube and located in a groove, *k*, in the said support *d*, and a groove, *l*, also in the part *d*, said groove containing the spring *f*, which is fixed at the right-hand end of the groove *l*, and the coil-spring *c*, pressing against that end of the support *d* farthest from the brush *e*.

When it is desired to put the brush into the pocket, the button *g* is pressed through the hole *h'*, and the support *d* is pushed into the tube *a* until the button *g* springs into the hole *h*, where it causes the brush to be re-

tained within the tube. A cap or cover, *m*, 50 may then be placed upon the open end, in order that the brush may be kept clean.

Referring particularly to Fig. 3, the brush may be placed in its extended position by simply pressing upon the catch or button *g*. The 55 spring *c* being under tension, forces the brush outwardly until the button *g* passes into the opening *h'*.

In order that the metal helical spring *c*, the metal spring *f*, and other metal portions may 60 be protected from the water while the brush is in use as well as when not in use, the tube *a* is made slightly longer, as shown in Fig. 8, and the support *d* carries a rubber membrane, *n*, which fits snugly in the tube *a*. 65 This membrane may slide back and forth with the brush *d*.

In order to usefully apply the membrane *n* to the construction shown in Figs. 1, 2, 3, 4, 5, 6, and 7, it may be necessary to vary the 70 proportional dimensions of the device, which can easily be done by those versed in the art.

The surface of the tube, which serves as a handle, may be covered outwardly with an ornamental coating of the substance known as 75 "agaloid."

It is evident that the coil or helical spring *c* need not be rigidly fixed to the end *b* of the tube *a*.

It is preferable to make the button *g* of a 80 harder substance than that of the tube *a*, in order to prevent its wearing out too quickly.

The proportional dimensions of the device may be altered without interfering with the spirit of the invention. 85

We claim as our invention—

1. In a tooth-brush, the combination of a tube closed at one end and open at the other and provided with apertures *h* and *h'*, a brush-support located in said tube, a spring between 90 the closed end of the tube and the brush-support, and a second spring having one end fastened to said support, the other end carrying a projection which fits in one of the apertures, and the second spring being located in a 95 groove in said brush-support, and suitable means for preventing the rotation of the brush-support in the tube.

2. In a tooth-brush, the combination of a tubular handle closed at one end, the sliding brush, and a rubber membrane mounted upon the stem of the brush and serving to close the 5 open end of the tubular handle when the brush is in its extended or open position.

In testimony that we claim the foregoing as

our invention we have signed our names in presence of two witnesses.

ADRIAN F. BOUTON.
KENT K. STEARNS.
